RAIL DETECTOR CONTROLLER FOR
DRAWBRIDGES

Glen V. Jefferson, Edgewood, Pa., assignor to
Westinghouse Air Brake Company, a corpora-
tion of Pennsylvania

Application August 31, 1948, Serial No. 47,101

3 Claims. (Cl. 246—118)

1

My invention relates to control apparatus arranged for operation in response to the position of a movable element.

My invention is disclosed herein as applied to an electric circuit controller operated in accordance with the position of the lift rail of a railway drawbridge. Although certain features of my invention are of especial utility in connection with such an arrangement, other features are of more general utility in connection with position responsive control apparatus.

The rail connections between the movable span and the fixed spans on a railway drawbridge are commonly made by providing lift rails on the end of one of each pair of adjacent span ends. Each lift rail has a normal or down position in which it abuts the fixed rail on the end of the adjacent span, and in which it may safely carry railway traffic. The lift rail is movable from its down position to an up position wherein it clears the other parts of the bridge sufficiently to permit opening of the draw. The lift rail is usually arranged to have a substantial range of overtravel beyond the up position. As long as the lift rail is in the up position or in the overtravel range, it will clear the bridge structure when the draw is opened.

The approaches to a drawbridge are provided with signals to inform the operator of approaching trains whether or not it is safe to proceed across the draw. It is desirable to arrange the signal controlling circuits so that the signals cannot be cleared if any of the lift rails is away from its down position.

Other signals may be provided to inform the drawbridge operator that the rail is up so that it is safe to swing the drawbridge. Such signals must also be controlled in accordance with the position of the lift rail. Electric signals are commonly used, and hence an electric circuit controller responsive to the lift rail position may be used to control the signals.

It is therefore an object of my invention to provide improved means for operating an electric circuit controller in response to the position of a lift rail on a railway drawbridge.

Another object is to provide improved control apparatus for checking both the down and up positions of such a lift rail.

A further object is to provide such control apparatus having increased sensitivity of response to rail movement when the rail is at or adjacent its down and up positions.

Another object of my invention is to provide control apparatus of type described including

2

improved means for avoiding undesirable effects due to expansion or contraction of the rails.

A further object of my invention is to provide an improved apparatus for operating a control device in response to the position of a movable member.

Another object of my invention is to provide an improved mechanism for operating the circuit controller associated with the lift rail of a railway drawbridge of the general type shown in the copending application for Letters Patent of the United States of Herbert L. Bone and William C. McWhirter, Serial No. 30,535, filed June 2, 1948, for Control Apparatus.

15 In carrying out my invention, I mount on the ties alongside the lift rail an electric circuit controller of the type described and claimed in the copending application of Herbert L. Bone and Glen V. Jefferson, Serial No. 1955, filed January 20 13, 1948. This circuit controller is provided with an operating crank arm having an outwardly extending projection mounted on its free end. A bracket is attached to the lift rail and carries at its free end another projection. A motion plate is mounted between the the circuit controller and the lift rail in suitable guides so that it can move only in a vertical direction. This motion plate is provided with a horizontal slot to receive the projection on the lift rail bracket and with a cam slot to receive the projection on the circuit controller crank arm.

As the lift rail rises, the projection on the bracket extending through the horizontal slot on the motion plate lifts the motion plate as the rail moves vertically. The horizontal slot in the motion plate permits horizontal movement of the rail independently of the motion plate. As the motion plate moves vertically, the crank arm of the circuit controller is operated 40 in accordance with the contour of the cam slot in the motion plate. This cam slot is contoured so as to provide an appreciable movement of the circuit controller crank arm when the lift rail is adjacent its down position and also when the lift rail is adjacent its up position. Between these two portions of the cam slot is a vertical portion which permits the rail to move upwardly between its down and up position without causing appreciable movement of the circuit controller. I provide another vertical portion of the cam slot beyond the portion corresponding to the up position of the rail, so that the circuit controller is not operated during the overtravel of the rail beyond its up position.

55 Other objects and characteristic features of

my invention will become apparent as the description proceeds.

I shall illustrate and describe herein only one modification of my invention, and shall then point out the novel features thereof in claims.

In the drawings, Fig. 1 is a plan view of a fragment of a railway drawbridge, showing the adjacent ends of a fixed rail and a lift rail, with one embodiment of my invention applied to the lift rail. Fig. 2 is an elevational view of the apparatus shown in Fig. 1 portions thereof being in section for illustrating to better advantage applicant's construction. Fig. 3 is a sectional view taken along the line III—III of Fig. 1. Fig. 4 is a sectional view of a circuit controller which may be used in the apparatus of Figs. 1-3.

Similar reference characters refer to similar parts in each of the several views.

Fig. 1 shows a rail connection between a movable span and a fixed span of a railway drawbridge, including a fixed rail 1 and a lift rail 2. The fixed rail is rigidly mounted on the ties (not shown). The lift rail rests in a rail chair 3 attached to the ties, and may be lifted from the chair by suitable driving mechanism not shown, the lift rail having fixed thereto oppositely extending guides 2a for centering the rail within the rail chair 3. Attached to the outer side of the web of lift rail 2 is a bracket 4, which carries at its outer end an outwardly projecting pin 5.

A motion plate 6 extends downwardly in a vertical slot 7a cut into the tie and is guided for vertical movement by guides 7. The motion plate 6 is provided with a horizontal slot 6a which receives the pin 5 on the end of bracket 4. It may be seen that as the rail 2 is lifted, the engagement of pin 5 with slot 6a causes the motion plate 6 to follow the vertical movement of the lift rail. The horizontal slot 6a permits the rail 2 to move horizontally without affecting the position of motion plate 6. The motion of pin 5 is along an arcuate path rather than a straight vertical line, and the slot 6a accommodates the horizontal component of that motion. Horizontal movement of the rail 2 may also be occasioned, for example, by expansion and contraction of the rail due to temperature changes.

A circuit controller 8 is mounted on the ties adjacent the motion plate 6. The controller 8 has an operating shaft 9 carrying a crank arm 10. The crank arm 10 carries at its end a pin 11 which is received in a cam slot 12 in the motion plate 6.

The cam slot 12 has a curved portion 12a which receives the pin 11 when the rail 2 is adjacent its down position, a vertical portion 12b which receives the pin 11 as the rail moves upwardly from its down position, another curved portion 12c which receives the pin 11 when the rail is adjacent its up position, and a vertical portion 12d which receives the pin 11 when the rail moves beyond its up position.

The circuit controller 8 is shown in greater detail in Fig. 4. It includes two cams 13a and two cams 13b, only one each of which appears in Fig. 4. These cams are carried by the shaft 9 and operate rocker arms 14 pivoted on a rock-shaft 15 and carrying followers 14a which cooperate with the cams. One end of each rocker arm 14 is connected through a link 16 to a movable contact 17. Each contact 17 engages a stationary contact 18, and is movable away from its stationary contact 18 and into engagement with a stationary contact 20. Only one rocker arm 14 and one set of contacts 17, 18, and 20 is illustrat-

ed in Fig. 4. It should be understood that each of the four cams 13a and 13b operates a similar rocker arm and contact set. The parts of the circuit controller are illustrated in Fig. 4 in the positions corresponding to the down position of the lift rail 2, as illustrated in Fig. 2.

The contacts 17 operated by the cams 13a are connected in the circuits of the signals which control the railway traffic moving across the drawbridge. When these contacts 17 engage their associated contacts 18, the signals are controlled to permit traffic movement over the bridge. When these contacts 17 engage their associated contacts 20, the signals are controlled to prevent traffic movement over the bridge.

The contacts 17 operated by the cams 13b are connected in the circuits of the signals which indicate whether or not it is safe to operate the swinging mechanism of the bridge. When these contacts 17 engage their associated contacts 18, these signals indicate that the lift rail is in a position where it will not clear the other parts of the bridge structure if the swing span is moved. When these contacts 17 engage their associated contacts 20, the signals indicate that the lift rail has reached its up position, and that it is safe to move the swing span.

Any suitable signal controlling circuits may be used in connection with my invention. The particular contact arrangement described herein is preferred, but other equivalent contact arrangements may be used with equal facility.

Operation

35 The parts are shown in their positions corresponding to the down position of the lift rail 2. The dotted lines in Fig. 2 show the lift rail in its up position and the corresponding positions of some of the parts. In the down position of the lift rail, it is ready to carry traffic over the bridge. In the circuit controller, the movable contacts 17 are engaging the stationary contacts 18.

45 Starting with the parts in the positions shown, let it be assumed that the lift rail 2 is moved toward its up position, which is illustrated in dotted lines in Fig. 2. As the rail 2 moves upwardly, engagement of pin 5 with slot 6a carries the motion plate 6 upwardly. The pin 11 on crank arm 10 engages curved portion 12a of the cam slot 12 in the motion plate 6. As the motion plate 6 starts upwardly, pin 11 is moved to the right in the cam slot portion 12a, thereby rotating the crank arm 10 counterclockwise. As the crank arm 10 and shaft 9 starts to move counterclockwise from the position shown, the two cams 13a operate their associated rocker arms 14 to move their respective contacts 17 away from their contacts 18 and into engagement with their contacts 20. No further movement of these contacts 17 takes place.

55 When the lift rail reaches its up position, wherein the rail is sufficiently clear of the other parts of the bridge to permit opening of the draw, then the pin 11 moves into the curved portion 12c of the cam slot. As the pin 11 moves through the portion 12c of the cam slot, crank arm 10 is rotated additionally counterclockwise. The corresponding counterclockwise rotation of shaft 9 operates the cams 13b to move their contacts 17 out of engagement with their contacts 18 and into engagement with their respective contact 20. As previously mentioned, this contact movement completes a signal circuit for indicating to the bridge operator that it is safe to proceed with the opening of the draw.

After this operation of the circuit controller 8 by the crank arm 10 is completed, the lift rail 2 may continue to move upward in accordance with the overtravel provision of its driving mechanism. During this phase of its movement, the pin 11 rides in the vertical portion 12d of the cam slot 12, and therefore does not cause any additional operation of the circuit controller 8.

During the downward movement of the lift rail, the operation of the circuit controller is just the reverse of that previously described for the upward movement. The cams 13b are operated to move their contacts 17 away from their contacts 20 and into engagement with the contacts 18 as the pin passes through the curved portion 12c of the cam slot. The contacts 17 operated by cams 13a are moved away from their contacts 20 and restored to engagement with their contacts 18 when the lift rail 2 reaches its down position and the pin 11 moves through the curved portion 12a of the cam slot.

Although I have herein shown and described only one modification of control apparatus embodying my invention, it is understood that various changes and modifications may be made therein within the scope of the appended claims without departing from the spirit and scope of my invention.

Having thus described my invention, what I claim is:

1. Apparatus for operating a circuit controller in accordance with the position of the lift rail of a railway drawbridge, comprising a projection on the lift rail, a lever arm operatively connected to the circuit controller and having a follower projecting therefrom, and a motion plate guided for vertical movement and having a horizontal slot to receive said projection so that it follows vertical movements of the lift rail but is not affected by horizontal movements of the rail, said motion plate having a cam slot to receive said follower, said cam slot being contoured to rotate the lever arm and operate the circuit controller as the motion plate moves vertically.

2. Apparatus for operating a circuit controller in accordance with the position of the lift rail of a railway drawbridge, said lift rail being movable between a down position wherein it can carry railway traffic and an up position wherein it clears other parts of the bridge sufficiently to permit opening of the draw, comprising a projection on the lift rail, a lever arm operatively connected to

the circuit controller and having a follower projecting therefrom, and a motion plate guided for vertical movement and having a horizontal slot to receive said projection so that it follows vertical movements of the lift rail but is not affected by horizontal movements of the rail, said motion plate having a cam slot to receive said follower, said cam slot being contoured to rotate the lever arm and operate the circuit controller from a first circuit-controlling position to a second circuit-controlling position as the lift rail moves upwardly from its down position, to hold the lever arm substantially stationary thereafter during continued upward movement of the lift rail until the rail approaches its up position, to rotate the lever arm and operate the circuit controller from its second circuit-controlling position to a third circuit-controlling position as the rail moves to its up position, and to hold the lever arm substantially stationary thereafter during overtravel of the lift rail beyond its up position.

3. Control apparatus to be operated in accordance with the position of the lift rail of a railway drawbridge, comprising an electric circuit controller, a first member connected to the lift rail for concurrent movement therewith, said first member having a first projection thereon, a second member connected to the circuit controller for concurrent movement therewith and having a second projection thereon, and a third member guided for movement along a fixed path, said third member having a horizontal slot which receives said first projection and causes the third member to move along said fixed path as the first member moves vertically but permits independent horizontal movement of the first member, said third member also having a cam slot which receives said second projection and causes the second member to move and operate the circuit controller as said third member moves along said path.

GLEN V. JEFFERSON.
